US0D1063484S

(12) **United States Design Patent** (10) **Patent No.:** **US D1,063,484 S**
(45) **Date of Patent:** **** Feb. 25, 2025**

(54) **DEFROSTER**

(71) Applicant: **Yi Guan**, Shanghai (CN)

(72) Inventor: **Yi Guan**, Shanghai (CN)

(**) Term: **15 Years**

(21) Appl. No.: **29/889,345**

(22) Filed: **Apr. 11, 2023**

(51) LOC (15) Cl. **07-02**

(52) U.S. Cl.

USPC **D7/365**

(58) **Field of Classification Search**

(57) **CLAIM**

The ornamental design for a defroster, as shown and described.

DESCRIPTION

FIG. 1 is a perspective view of my new design, showing a defroster;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view of the defroster.

The line shading in FIGS. 1-8 represents contour and not surface ornamentation and the broken lines shown in the figures illustrate environmental or other features that form no part of the claimed design.

1 Claim, 8 Drawing Sheets
